ABSTRACT OF THE DISCLOSURE

A deformable clamp for sealing packages which has, in the undeformed state, a U-shape to receive the neck of a package to be sealed, and a pair of legs which can be bent inwardly into a deformed state to encompass the package neck to seal the package, the transverse cross section area of the clamp being symmetrical about the central plane of the clamp and having its maximum dimension line located in such plane to provide an increased specific sealing pressure around the neck contact region.

This invention relates to a sealing clamp for closing packages made of a flexible material, such as sausage skins and bags for packaging foodstuffs, which may be made of plastic foil. Previously proposed sealing clamps consist of a deformable U-shaped member having circular, square, rectangular or also strip-like cross section. The previously twisted or ruffled ends of a package are gripped by the clamp by bending the two outer legs of the clamp inwardly. However, the clamp has to withstand the static restoring forces acting on the legs in order to avoid a reopening of the package if a liquid or airtight closure is to be maintained.

The proposed sealing clamps are sometimes inadequate to maintain a fluid-tight closure, especially when external forces are added to the restoring force acting on the legs. These external forces may be caused during the transport of the closed packages, where vibratory movements arise. If the clamp-sealed packages are in fact sausages suspended in strings, there arises the additional danger that the dynamic forces generated by the weight of these objects will strip the clamp off the closure.

According to the invention there is provided a sealing clamp for packages made of flexible material, such as sausage skins and bags made of plastic foil for the packaging of foodstuffs, said clamp comprising a deformable U-shaped member having a substantially oval cross section, the major axis of the oval being located in the principal plane of the sealing clamp.

This arrangement offers several advantages. It provided a considerable increase of the moment of resistance for an equal volume of material, in relation to a circular cross section or a saving of material of the order of 15 to 20% for a given strength when compared with a clamp having circular cross section. Moreover, the clamps according to the invention are narrower, so that a correspondingly greater number of them can be accommodated in a magazine.

A further advantage arising from the narrowness of the clamps according to the invention is constituted by the fact that their surface of contact at the region of closure is smaller, which leads to an increase of the specific sealing pressure. This results in a tighter closure, without damage to the packing material at the closure region. Finally, the oval cross section proposed according to the invention also offers the advantage that it does not expand in width in the case of sharp bending movements in the zone of compression. Thus the clamps according to the invention can be lined up to form a straight stack for the magazine.

2

The ideal cross section for the sealing elements according to the invention is an ellipse. If preferred, a rhombic cross section with rounded longitudinal edges can also be employed. This cross section offers the advantage that it has plane regions on its periphery, which facilitate the guiding of the clamps in a magazine feeder.

According to another embodiment of the invention, the sealing clamp may also have a pear-shaped cross sectional profile, wherein the thicker portion of the drop-shape is directed towards the outside of the clamp and the tapering portion is directed inwards. With this cross sectional form, it is possible to avoid, during manufacture of the clamps, an internal thickening within the bending radius region, which would be greater than the profile, and the stronger cross section is located on the outside, namely in the stretching zone where the stresses are larger.

According to another embodiment of the invention, the ends of the two legs of the clamp are chamfered on their outer edges. This leads to the additional advantage of facilitating the sliding of the legs during setting up on a bolster and in the subsequent closing operation, ensuring a smoother rolling-on movement. This in turn reduces the specific load during the placing of the front-end edges of the clamps on the bolster, thus avoiding crushed edges, which could damage the packaging material by forming sharp ridges. The chamfering of the edges can be performed during manufacture of the clamps, for example by upsetting, which hardens the leg end edges. The hardening of these edges additionally facilitates sliding during the rolling movement of the legs into a die for closure thereof. The upsetting process also leads to recovery of material. Due to the improved sliding ability during closure the closed clamp has greater buckling radii, whereas poor sliding within the die mostly leads to the formation of acute angles at the buckling points, in which the enclosed packaging material may be crushed. Consequently, a material having high strength can be employed, having a correspondingly greater amount of resistance and being cheaper to produce.

It is therefore, an object of the invention to provide a deformable clamp for sealing packages which affords a high specific sealing pressure.

Another object of the invention is to provide a sealing clamp as aforesaid which when deformed around the neck of a package to be sealed will effectively seal the package without damaging the packaging material.

A further object of the invention is to provide a sealing clamp as aforesaid which in the deformed state will effectively resist the resilient forces exerted by the packaging material that tend to open the clamp and unseal the package.

Other and further objects and advantages of the invention will become apparent from the following detailed description and accompanying drawing in which:

FIG. 1 shows a clamp according to a preferred embodiment of the invention as viewed in the undeformed state and in a direction normal to the principal plane of the clamp.

FIG. 2 is a side view of the clamp of FIG. 1 as seen at a section taken along line II—II therein.

FIG. 3 is a side view of a clamp according to another embodiment of the invention, which clamp has a rounded corner rhombic transverse cross section as seen at a section taken similar to that in FIG. 2.

FIG. 4 is a side view of a clamp according to a further embodiment of the invention, which clamp has a pear-shaped transverse cross section as seen at a section taken similar to those in FIGS. 2 and 3.

FIG. 5 shows the clamp of FIG. 1 as it appears in its ultimate deformed state to seal the neck of a package.

FIG. 6 shows a prior art U-shaped clamp in a deformed package sealing state illustrating the acute

angles formed at the leg bending points and the protruding leg end edges resulting from the lack of chamfered leg ends.

Referring to FIGS. 1 and 2, a U-shaped clamp 1 has an oval transverse cross section area indicated at 2. The major axis 3 of cross section 2 is located in the common plane 4 of clamp 1. During inward bending of legs 5 of the clamp there is no expansion in the curved length sections 6 beyond the external dimensions obtaining in the region of the minor axis 7 of the oval cross section 2. Thus a plurality of clamps 1 can be tightly packed against each other in a magazine (not shown), without having to maintain an enlarged spacing in the regions 6 owing to outward expansion of the material. This is the case in particular with prior art clamps having rectangular cross section (not shown). Due to the oval cross section 2 the bulges of material in the regions 6 are confined between the outer boundaries 8 of clamp 1.

The same advantages are offered by the clamps 9 and 16, illustrated in FIGS. 3 and 4 respectively. The transverse cross section area 10 of clamp 9 is likewise substantially oval, but strictly speaking it is a rhombus with rounded corners. Consequently, cross section 10 has four flat regions 11, plane regions when viewed in longitudinal direction of clamp 9. These regions 11 offer the particular advantage of good clamp guidance from a magazine to the point of closure. The clamp 16 shown in FIG. 4 has a pear-shaped transverse cross section area 17, the thick portion of which is directed outwards and the tapering portion is directed inwards.

The free leg 5 ends of the clamps 1, 9, 16 are preferably chamfered on their outer edges, as at 12 in FIG. 1.

These sloped or chamfered edges 12 may be produced by upsetting. Without such chamfered leg ends 12, the closed clamp will have in most cases an undesirable ridge 13, as shown by FIG. 6. If the ends of the legs 5 are sloped it is possible to make the clamps 1, 9, 16 of a material which will preserve the radii 14 as shown in FIG. 5. When the ends of the shanks are not acute angles 15 are formed upon deformation as shown in FIG. 6.

As can be appreciated from the foregoing, the invention provides a deformable clamp member, having in the undeformed state a U-shape defined by a central length portion x and a pair of outer legs 5 integrally connected to central portion x each by a curved length section 6.

All transverse cross section areas of clamp 1, 9, 16 as can be seen from FIGS. 2, 3 and 4, are symmetrical with respect to a common plane, namely the principal plane 4, and the various cross sectional areas 2, 10 and 17 each have a singular line of maximum dimension lying in plane 4.

The legs 5 are spaced apart for receiving therebetween and against central portion x and also curved sections 6, the neck N (shown in FIG. 1 in phantom) of a package (not shown) to be sealed. Legs 5 are disposed for bending inwardly, together with curved sections 6, toward central portion x into a deformed state as illustrated by FIG. 5, so as to encompass the neck N and compress same to seal the package. The free ends of legs 5 are chamfered as at 12 for the purpose of assisting inward bending deformation by compressive forces applied to their free ends, as for example, in a clamp closing die (not shown).

It has been found that satisfactory performance of the various cross sectioned clamps 1, 9, 16 according to the invention can be generally obtained where the ratio of the maximum transverse cross sectional area dimension to the mean radius of the curved length sections 6 is within the range 3:1 to 1:2. In the case of the elliptical cross section clamp 1 of FIGS. 1 and 2, the ratio of the major axis 3 dimension to the minor axis 7 dimension is preferably within the range 2:1 to 1.2:1.

Regardless of the particular transverse cross section chosen, the clamps 1, 9, 16 are preferably of uniform

cross sectional dimensions, and have legs 5 of equal length, with the length dimension ratio between the central portion and legs 5 within the range of 1:1.2 to 1:2.

From the foregoing description of the invention, it will become apparent to the artisan that the invention is susceptible of numerous obvious modifications and variations.

What is claimed is:

1. A clamp for sealing packages which comprises a deformable member of a cross section having major and minor axes, wherein the major axis is of a dimension greater than said minor axis, said member having in the undeformed state a U-shape defined by a central portion and a pair of outer leg portions integrally connected to said central portion each by a curved length section, all transverse cross sectional areas of said central portion, leg portions and curved length sections being uniform throughout substantially the linear extent thereof and being symmetrical with respect to a common plane and having a singular line of maximum dimension corresponding to said major axis lying in said plane, the surface of said central portion and said leg portions at the interior of said maximum dimension with respect to said U-shape being round, said leg portions being spaced apart for receiving therebetween and against said central portion and curved length sections the neck of a package to be sealed, said leg portions being disposed for bending inwardly, together with their respective curved length sections, toward said central portion into a deformed state to encompass said package neck and compress same to seal the package.

2. The clamp according to claim 1 wherein said central portion, outer leg portions and curved length sections have oval transverse cross sectional areas.

3. The clamp according to claim 1 wherein said central portion, outer leg portions and curved length sections have elliptical transverse cross sectional areas.

4. The clamp according to claim 1 wherein said central portion, outer leg portions and curved length sections have rounded corner rhombic transverse cross sectional areas.

5. The clamp according to claim 1 wherein said central portion, outer leg portions and curved length sections have pear-shaped transverse cross sectional areas oriented for compressive contact with the package neck along their minimum radius portions.

6. The clamp according to claim 1 wherein said central portion, outer leg portions and curved length sections have uniform transverse cross sectional areas.

7. The clamp according to claim 1 wherein the free ends of said outer leg portions are chamfered at the exterior thereof to assist inward bending deformation thereof by compressive forces applied to said free ends.

8. The clamp according to claim 1 wherein the ratio of said maximum transverse cross sectional area dimension to the mean radius of said curved length sections is within the range 3:1 to 1:2.

9. The clamp according to claim 3 wherein the ratio of the major axis dimension to the minor axis dimension of said elliptical transverse cross sectional area is within the range 2:1 to 1.2:1.

10. The clamp according to claim 1 wherein said outer leg portions are of uniform length, and the length dimension ratio between the central portion and said outer leg portions is within the range 1:1.2 to 1:2.

11. A package comprising wrapping sheet material having a neck closed by an elongated clamp comprising a deformable member of a cross section having major and minor axes, wherein the major axis is of a dimension greater than that of said minor axis, said member being defined by a central portion and a pair of leg portions integrally connected to said central portion each by a curved length section, all transverse cross-sectional areas of said central portion, leg portions and curved length sections being symmetrical with respect to a common plane and having a singular line of maximum dimension cor-

responding to said major axis lying in said plane, said leg portions being bent back over the central portion and disposed in substantial meeting relation, the clamp compressing the wrapping sheet material to seal the package at said neck.
